(57) **CLAIM**

The ornamental design for a device for securing a guardrail to a roof portion, as shown and described.

DESCRIPTION

FIG. 1 is a front perspective view of a device for securing a guardrail to a roof portion;

FIG. 2 is an exploded view thereof;

FIG. 3 is a left-side elevation view thereof;

FIG. 4 is a left-side elevation view of FIG. 2 secured to a roof portion; the broken lines depict environment that forms no part of the claimed design;

FIG. 5 is a front elevation view of FIG. 1;

FIG. 6 is a front elevation view of FIG. 2 secured to a roof portion; the broken lines depict environment that forms no part of the claimed design;

FIG. 7 is a back elevation view of FIG. 1;

FIG. 8 is a back elevation view of FIG. 1 secured to a roof portion; the broken lines depict environment that forms no part of the claimed design;

FIG. 9 is a top plan view of FIG. 1; and,

FIG. 10 is a bottom plan view of FIG. 1.

1 Claim, 9 Drawing Sheets
